UNITED STATES PATENT OFFICE.

HARRY W. HILL, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

LENS HOLDER.

Application filed November 23, 1920. Serial No. 426,006.

To all whom it may concern:

Be it known that I, HARRY W. HILL, a citizen of the United States, residing at Southbridge, in the county of Worcester and 5 State of Massachusetts, have invented certain new and useful Improvements in Lens Holders, of which the following is a specification.

This invention relates to improvements 10 in lens holders and has particular reference to a mechanical form of lens holder as distinguished from those now commercially used and also those of the prior art.

It is, therefore, the purpose of my invention to obviate these prior art difficulties and 15 to provide new and novel means for mechanically holding the lenses without the use of adhesive, so that there is no special labor of blocking and no subsequent cleaning or removing of the blocking adhesive required.

Other objects and advantages of my improvement should be readily apparent by reference to the following specification taken 20 in connection with the accompanying drawings, and it will be understood that I may make any modifications in the specific details of construction shown and described 25 within the scope of the appended claims without departing from or exceeding the spirit of my invention.

Figure I represents a view of one embodiment of my invention in use.

Figure II represents a bottom plan view 30 of the structure as illustrated in Figure I.

Figure III represents a top plan view thereof.

Figure IV represents a sectional view as 35 on the line IV—IV of Figure III.

Figure V represents a sectional view of 40 this particular type of mechanism in use.

In the accomplishment of this result I make use of an improved block comprising the body portion 1 having the upstanding 45 socketed portion 2 to rotatably receive the lens pin 3. This body portion is provided with a plurality of radiating arms or lugs 4 which have been illustrated as substantially triangular in form with the base of 50 the triangle outward. On each of the sides of the triangle adjacent the base I have shown as formed the arcuate lugs or fingers 5 so positioned as to properly engage the edges of a lens 6, the lens here being shown

as a circular form and the fingers 5 of the 55 proper form and size to just receive and satisfactorily fit around the portion of lens opposed thereto. Secured to the back of each of the members 4 is the heavy spring member 7 having the depending ends 8 60 which project above the lens seat 9 and serve to grippingly engage the edge of the lens member 6, the pressure of the springs 8 being in the direction of the seats 5.

This is of particular advantage since 65 while the lenses may be easily snapped into place by being placed in engagement with the members 5 and pressed against the slightly flared spring ends 8, or may be removed by pressing against the edge of the 70 lens overhanging the base of the triangular lug 4, at the same time the pressure of the grinding tool 10, as shown in Figure V, is such as to separate or force the lenses outwardly. This outward forcing, it will be 75 seen, supplements the action of the springs 8 so that the lens is at all times held out or against the rigid stationary lugs on the holder, being supplemented by the action 80 of the springs so that the greater the grinding pressure the more securely the lenses are held, in place of being loosened as might be the case where the springs at the outer instead of at the inner side of the block.

It is to be noted that in the drawings I 85 have shown my invention with the seats 9 so disposed as to properly support the lens blank 6 to have but a segment or recess 11 ground in their faces in place of the whole 90 lens being ground, but this is purely a matter of choice and my invention is equally applicable whether but a portion or the entirety of the lens is being ground.

I claim:

1. A device of the character described 95 comprising a body portion having a pin receiving socket and a plurality of radiating arms, each of said arms being formed with a lens receiving seat and with terminal projections adjacent the seat, and U-shaped 100 spring members secured to and spanning the inner portions of each of the arms and having their ends projecting beyond the seats to resiliently engage a lens and press it in the direction of the projections.

2. A device of the character described 105 including a plurality of lens seats having rigid lens engaging members at their outer

sides and resilient lens engaging members at their inner sides.

3. A device of the character described including a plurality of divergent arms disposed in angular relation one to the other, each of said arms being provided with a lens receiving seat, each of said arms being further provided with rigid lens abutment lugs to prevent movement of the lens over 10 the seat as actuated by pressure against the tool, and being further provided with resilient means for retaining the blank in engagement with said rigid means.

4. In a device of the character described

the combination with a body portion having 15 a lens receiving seat and having a plurality of rigid lugs projecting adjacent the seat, of a U-shaped clamp member secured to the body portion and having the terminals of the U projecting adjacent the seat and in 20 position to oppose the lugs and resiliently force the lens thereagainst.

In testimony whereof I have affixed my signature, in presence of two witnesses.

HARRY W. HILL.

Witnesses:

ALICE G. HASKELL,
ESTHER M. LATLER.
